UNITED STATES PATENT OFFICE.

KNUT LUDWIG STENDAHL, OF BRIDGEPORT, CONNECTICUT, ASSIGNOR TO THE HURWOOD MANUFACTURING COMPANY, INCORPORATED, OF BRIDGEPORT, CONNECTICUT, A CORPORATION OF CONNECTICUT.

COLD-BLAST LANTERN.

No. 921,022.

Specification of Letters Patent.

Patented May 11, 1909.

Application filed July 8, 1908. Serial No. 442,586.

To all whom it may concern:

Be it known that I, KNUT LUDWIG STENDAHL, a citizen of the United States, residing at Bridgeport, county of Fairfield, State of Connecticut, have invented a new and useful Cold-Blast Lantern, of which the following is a specification.

This invention relates to the class of lanterns known as cold blast lanterns and has for its object to simplify, cheapen and to greatly improve the construction of the globe lifting and chimney lifting mechanism so that the chimney will be lifted entirely clear of the globe and the latter may be swung aside.

With these and other objects in view I have devised the novel construction of which the following description in connection with the accompanying drawings is a specification, reference characters being used to designate the several parts.

Figure 1 is an elevation of my novel lantern, the dome and chimney being partly broken away to illustrate the chimney lifting mechanism; Fig. 2 a section on the line 2—2 in Fig. 1 looking down; Fig. 3 an elevation showing the globe and chimney raised and the globe partly swung aside; and Fig. 4 is a section on the line 4—4 in Fig. 3 looking down.

10 10 denotes the font, 11 and 12 the side tubes, 13 the dome which is carried by the side tubes, 14 the chimney, 15 the canopy which is carried by the chimney, 16 the globe, 17 the rest by which the globe was carried 35 and 18 the burner.

My novel globe and chimney lifting mechanism comprises essentially a shaft 19 which is journaled in the side tubes near their lower ends and is provided at one end with an operating lever indicated by 20. The mid length of the shaft is deflected to form a crank arm 21 which is pivotally connected to the globe rest as by an eye 22 on the under side of the rest through which the crank arm slides.

40 23 denotes a lifting rod which extends from the globe rest and then upward parallel with side tube 11.

24 denotes guides on the side tube in which the lifting rod oscillates and slides freely. At 50 the upper end of the lifting rod is a head 25 provided with a guide 26.

27 denotes globe guards attached to the rest, one of which is shown as attached to the head.

28 denotes the chimney lifting rod which 55 extends upward and inward under the dome and through a slot 29 in the chimney. The vertical portion of rod 28 slides in a guide 30 on side tube 11, passes through guide 26 on head 25 and is provided at its lower end with 60 an enlargement 31 which lies between head 25 and guide 26 resting on the head and retaining the chimney lifting rod against longitudinal movement independently of lifting rod 23. The upper end of the chimney lifting 65 rod is shaped to form a head 32 which passes through and engages a link 33, the outer end of which passes through slot 29 in the chimney and engages a cross pin 34 in side tube 11, the inner end engaging a cross pin 35 in 70 the chimney. At the lower end of the chimney is a strengthening ring 36 made of wire and provided with depending loops 37 which serve as stops to steady the globe and retain it in operative position. The globe may be 75 readily removed, when swung aside as in Fig. 3, by springing guards 27 sufficiently to permit it to be lifted from the rest.

38 denotes a locking catch on side tube 12 which is adapted to be engaged by the operating lever to lock said lever in place and with it the globe rest, globe and chimney when said parts are in their normal or operative position as in Fig. 1.

The operation is as follows: To raise the 85 globe and chimney the operator disengages the operating lever from catch 38 and swings the lever downward as in Fig. 3. This oscillates the shaft and causes the crank arm to lift the rest and globe swinging them side- 90 wise, as clearly shown in Figs. 3 and 4. The upward movement of lifting rod 23 raises the chimney lifting rod and with it the chimney through the engagement of head 25 with enlargement 31 and the engagement of head 95 32 on the chimney lifting rod with link 33 (see Figs. 1 and 3). It should be noted as an important feature of the present invention that the link is so positioned and so engaged by the head on the chimney lifting 100 rod that the chimney is raised slightly faster than the globe and above the globe so that the latter is free to swing laterally. This construction renders it unnecessary for the operator to touch the chimney in use under 105 any conditions likely to arise. Backward movement of the operating lever from the position shown in Fig. 3 raises the rest,

globe and chimney and then swings it backward and downward to the position shown in Fig. 1, the top of the globe resting against loops 37 on strengthening ring 36.

5 Having thus described my invention, I claim:

1. In a lantern, the combination with a globe rest, a lifting rod carried thereby and means for imparting vertical and swinging 10 movement to said parts, of a chimney normally resting on the globe, a chimney lifting rod engaged by the lifting rod and connections intermediate the chimney lifting rod and the chimney, whereby the chimney is raised above the globe when the latter is raised.

2. In a lantern, the combination with a globe rest having vertical and swinging movement, a lifting rod carried thereby and 20 a shaft having a crank arm engaging the rest which is raised, lowered and swung aside by oscillation of the shaft, of a chimney normally resting on the globe and a chimney lifting rod engaging the chimney and engaged by the lifting rod to raise the chimney above the globe when the latter is raised.

3. In a lantern, the combination with a globe rest having vertical and swinging movement and a chimney having vertical 30 movement, of a shaft having a crank arm engaging the globe rest with a sliding connection and connections intermediate the chimney and the globe rest whereby the chimney is raised above the globe to permit 35 the latter to be swung aside and is lowered upon the latter when it is returned to its normal position.

4. In a lantern, the combination with a globe rest having vertical and swinging 40 movement and a chimney, of a vertically movable chimney lifting rod, a link intermediate said rod and the chimney, and a vertically movable lifting rod connected to the globe rest and engaging the chimney lifting 45 rod.

5. In a lantern, the combination with side tubes and a vertically movable chimney, of a chimney lifting rod having longitudinal movement on a side tube, a link intermediate the 50 chimney lifting rod and the chimney, a lifting rod upon which the chimney lifting rod rests and which is connected to a side tube, a globe rest by which the lifting rod is carried and means for lifting the globe rest.

55 6. In a lantern, the combination with side tubes, and a vertically movable chimney, of a chimney lifting rod longitudinally movable on a side tube and connected to the chimney, a shaft journaled in the side tubes and having a crank arm, a globe rest pivotally and

slidably connected to the crank arm and a lifting rod extending from the globe rest and engaging the chimney lifting rod.

7. In a lantern, the combination with a globe rest and a chimney, of a shaft having a crank arm pivotally and slidably connected to said rest, a lifting rod extending from the globe rest and having a head and a guide, and a chimney lifting rod which engages the chimney, passes through the guide and is provided with an enlargement below the guide which is engaged by the head, whereby the chimney is raised above the globe when the latter is raised and swung sidewise by oscillation of the shaft. 75

8. In a lantern, the combination with a globe rest, a globe carried thereby and a chimney, of a shaft having a crank arm pivotally and slidably connected to the globe rest, a lifting rod extending from the globe rest and having a head and a guide, a chimney lifting rod connected to the chimney which engages the guide and rests upon the head and a strengthening ring on the chimney having loops against which the globe rests in its normal position. 80

9. In a lantern, the combination with a globe rest having vertical movement and a chimney, of a vertically movable chimney lifting rod having a head, a link connected to the chimney and engaged by the head and a vertically movable lifting rod connected to the globe rest by which the chimney lifting rod is engaged. 90

10. In a lantern, the combination with a globe rest having vertical movement and a chimney, of a vertically movable chimney lifting rod having a head, a link engaged by the head, cross pins passing through the ends of the link, one of which is within the chimney, and a vertically movable lifting rod connected to the globe rest by which the chimney lifting rod is engaged. 95

11. In a lantern, the combination with a globe rest having vertical movement and a chimney having a slot, of a vertically movable chimney lifting rod passing through said slot and having a head, a link passing through the slot in the chimney and engaged by the head within the chimney, cross pins passing through the ends of the link and a vertically movable lifting rod connected to the globe rest by which the chimney lifting rod is engaged. 105

In testimony whereof I affix my signature, in presence of two witnesses.

KNUT LUDWIG STENDAHL.
